UNITED STATES PATENT OFFICE.

GEORG PUMBERGER, OF EBERSCHWANG, AUSTRIA-HUNGARY.

METHOD OF WORKING SHIP-LOCKS.

No. 872,082.

Specification of Letters Patent.

Patented Nov. 26, 1907.

Application filed June 30, 1906. Serial No. 324,109.

To all whom it may concern:

Be it known that I, GEORG PUMBERGER, landowner, subject of the Emperor of Austria-Hungary, residing at Eberschwang, Austria-Hungary, have invented a new and useful Method of Working Ship-Locks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of the present invention is to provide for operating canal locks much more quickly and with much less commotion or disturbance in the water than is now possible; a further object is to effect a material saving in the quantity of water which passes through the lock on each operation thereof in order to convey a vessel from the lower to the higher level, or vice versa.

In the operation of the ordinary lock, it is necessary on each occasion thereof to lose so much water as represents the capacity of the lock from the level of the body of water in the lower canal to that of the body of water in the upper canal. In order to avoid this loss, 25 it has been proposed to provide, adjacent the lock, reservoirs into which the water of the filled lock, on the successive emptyings thereof, may be, in part at least, disposed. That is to say, a series of superposed chambers or 30 reservoirs being arranged near the lock, and the highest of said reservoirs being lower than the extreme elevation of the water in the lock, by providing each of such reservoirs with valves controlling the flow from the lock

35 into said reservoir, a saving of the water necessary to operate the lock may be effected in the following manner: The valves of all the reservoirs being closed, that of the uppermost one is opened. The communication 40 being thus established between the uppermost reservoir and the lock, the level in the latter falls to an extent commensurate with the capacity of said reservoir. The valve of the uppermost reservoir is then closed, and 45 that of the next highest opened and communication thus being now established between the second reservoir and the lock, the level in the latter again drops to an extent commensurate with the capacity of the second reservoir. 50 These operations continue until all of the reservoirs have been filled, each being

opened, then filled, and then closed before the next subjacent reservoir is opened. Thus, given a series of superposed reservoirs whose combined capacity is equal to two thirds of the capacity of the lock, and assuming that the extreme elevation of the uppermost reservoir is at least so much lower than the extreme elevation of the water in the lock as is equal to the vertical dimension of each reservoir, two thirds of the contents of the lock may be taken up by and stored in the reservoirs to be used on a subsequent operation of the lock towards filling the latter. The reason for this is of course the fact that the level of the entire body of water is maintained at all times lower in the next available reservoir than what it is in the lock itself. Of course, there is a waste of the ultimate one third of the water in the lock, which is allowed to flow off in the lower water of the canal on the opening of the lower lock gates.

In view of the foregoing my present invention will be understood on reference to the following description and the accompanying drawing, in which,

Figure 1 is a semi diagrammatical view in vertical section of a lock constructed in accordance with the principles of my invention; Fig. 2 is a similar view showing a horizontal section of the improved lock taken in a plane above the conduits *e*; Fig. 3 is an enlarged vertical sectional detail view of the upper portion of the lock; and, Fig. 4 is a view taken at right angles to Fig. 3 centrally of the lock proper.

In said drawing A designates the upper canal, B the lower canal, C the lock basin or lock proper and D, D' the gates of the lock proper.

95 Parallel with the lock and above the level of its base is a longitudinal conduit *d* which may communicate with the lock C by means of the ports *c*. At one side of the lock are arranged the reservoirs 1', 1, 2, 3, 4, 5, 6, 7, 8 and 8', the same being separated by a vertical conduit *e* which may communicate with the conduit *d* by the ports *e*'. The reservoirs 1, 2, 3, 4, 5, 6, 7, and 8 are arranged in staggered disposition; that is to say, reservoirs 2, 4, 6 and 8 are disposed the depth of one reservoir lower than the corresponding reservoirs 1, 3, 5 and 7; the reservoirs 1' and 8' occupy the spaces between the top of reservoir 2 and the horizontal plane of the top of reservoir 1', and the bottom of reservoir 7 and the horizontal plane of the bottom of

reservoir 8. As will be explained later, each reservoir is provided with a valve or door whereby it may be entirely closed off from the conduit *e*.

5 In practice, if the reservoirs were arranged only in one superposed series, the combined capacity of the reservoirs would be limited owing to the masonry which would be necessary between them; the arrangement above 10 described, whereby the reservoirs are staggered, permits a larger quantity of water to be accumulated in the series of reservoirs for the same vertical dimension of the whole reservoir series. Furthermore, it will be obvious 15 that to fill each reservoir completely before filling the next subjacent reservoir is objectionable, partly because the consequent intermittent exit of the water from the lock would be irregular and thus cause more or less disturbance in the lock and partly because time would be lost. I therefore propose 20 to admit the water to the reservoirs as follows: Reservoir 1' is first opened, and then when the level therein has reached a point 25 corresponding to the lower half of its capacity (it having about two thirds of the capacity of reservoir 1) reservoir 1 is opened; while reservoir 1 is filling to one third of its capacity the remaining half of the capacity 30 of reservoir 1' is filled; reservoir 1' is then closed and reservoir 2 opened, and while reservoir 2 is filling to one third of its capacity, reservoir 1 is filling to two thirds of its capacity; reservoir 3 is then opened and while it is 35 filling to one third of its capacity reservoir 2 is filling to two thirds of its capacity and reservoir 1 to its full capacity. This operation is continued downwardly throughout the reservoirs, one after the other, and as each 40 reservoir is filled it is of course at once closed. By these operations the water in the lock is quickly and gradually taken therefrom and stored in the reservoirs with a considerable saving of time.

45 Assuming that while the water is being thus stored in the reservoirs, a vessel is being lowered in the lock, by the time the reservoirs are filled, the new level assumed by the vessel will be that of the water remaining in 50 the lock. The gates D' are then operated to permit the level in the lock to completely assume the level of the lower canal, whereupon the vessel may pass out of the lock into the lower canal. Of course, should the next 55 vessel passing through the lock pass in the same direction there will be a loss of the full contents of the lock, because the reservoirs are filled at this time to their full capacity.

But should a vessel enter the lock going in the opposite direction, *i. e.*, toward the upper 60 canal level, then the lock does not need to be filled completely from the upper canal, since the water in the reservoirs is available for partly filling the lock. Therefore, since in most canals the traffic is about equally divided between the two directions, the reserve water in the reservoirs means a considerable saving of water for operating the lock.

65 In Figs. 3 and 4 I have shown in detail the means for operating the several valves for 70 the reservoirs. *k* is a conduit arranged over each of the reservoirs 1, 1'-8, 8' and communicating therewith at the inner end thereof, where a valve *l* is provided which, being in the form of a float, shuts off communication between said conduit and the corresponding reservoir when the level of the water rises to the float and falls, to open the valve, when the level in the reservoir falls. *x* denotes gates controlling the communication 75 between the reservoirs and the lock *C*, the same moving in grooves *m* in the masonry *y* of which the lock is constructed; *n* denotes rollers for easing the movement of the gates, the same moving on rails *o* in said 80 grooves. Each gate is formed with a rack *p* with which meshes a pinion *q* journaled in the masonry and in turn engaging with another rack *r* moving vertically in guides *r'* and engaging each at its upper end with a 85 gear *s* in mesh with the hand wheel *t* having a controlling hand gear attached thereto. By working the hand wheel *u* the gates can be opened and shut.

Having thus fully described my invention 95 what I claim as new and desire to secure by Letters Patent is:

The method of operating ship locks having annexed reservoirs disposed at different elevations which consists in causing the water 100 to flow into the uppermost reservoir from the lock and closing said reservoir when full, causing the water to flow into the next subjacent reservoir and closing it when full, and so on, downwardly, throughout the series of 105 reservoirs, each subjacent reservoir being opened upon the partial filling of the reservoir next relatively above it, substantially as described.

In testimony that I claim the foregoing I 110 have hereunto set my hand this 16th day of June, 1906.

GEORG PUMBERGER.
